UNITED STATES PATENT OFFICE.

MORRIS DOWLIN, OF HENNIKER, NEW HAMPSHIRE.

CLOCK STRIKING MECHANISM.

1,252,100.

Specification of Letters Patent.

Patented Jan. 1, 1918.

Application filed June 14, 1917. Serial No. 174,648.

To all whom it may concern:

Be it known that I, MORRIS DOWLIN, a citizen of the United States, and a resident of Henniker, in the county of Merrimack 5 and State of New Hampshire, have invented a new and Improved Clock Striking Mechanism, of which the following is a full, clear, and exact description.

The object of the invention is to provide 10 a new and improved clock striking mechanism of few and simple parts adapted for use in connection with any suitable make or model of striking clock and by means of which a clock so provided will sound full 15 hours and fractions of hours in distinct, definite, unmistakable, appropriate and pleasing sounds to correctly indicate the time of the day or night.

In order to produce the desired result, 20 use is made of two sounding devices, preferably of different pitch, two governors of different power controlling the striking mechanisms of the said sounding devices, the said governors being controlled by a 25 counting mechanism, such as a count wheel or a rack and snail, to cause striking of the full hours by slow strokes on one sounding device and while both governors are in action, and to cause sounding, by fast strokes, 30 of the preceding hour at a fraction of an hour and at the time one of the governors is out of action, to be preceded by the sounding of the second sounding device to denote a fraction of an hour.

35 A practical embodiment of the invention is represented in the accompanying drawings forming a part of this specification, in which similar characters of reference indicate corresponding parts in all the views.

40 Figure 1 is a rear elevation of the clock striking mechanism as applied and with the housing thereof shown in section;

Fig. 2 is a sectional front elevation of the same with the time controlling device omitted;

Fig. 3 is a rear elevation of the shifting mechanism for the slow governor with the parts in a different position from the one shown in Fig. 1;

50 Fig. 4 is a sectional rear elevation of the clock striking mechanism as applied and with the time controlling mechanism omitted;

Fig. 5 is a cross section of the same on the 55 line 5—5 of Fig. 4; and

Fig. 6 is a perspective view of the cam on

the hour shaft for moving one of the governors out of action.

The framework 10 carrying the clock movement is secured in a suitable housing 60 11 and on the said framework is mounted a going train 12 driven by a spring 13 and a striking train 14 driven by a spring 15. The going train is of the usual construction and drives the hour arbor 16 but as the said going train forms no part of my improvement further detail description of the same is not deemed necessary. The striking train controls two sounding devices of different pitch, preferably comprising hammers 20, 21, of 70 which the hammer 20 is adapted to strike and sound the hours on a gong 22 and the hammer 21 is adapted to strike and sound the half hours on a bell 23. It is understood that the clock striking mechanism is 75 arranged for sounding the full hours and the half hours, but I do not limit myself to this particular arrangement as other fractions of the hour, such as the quarter hour, the half hour and three-quarter hour may 80 be sounded. The striking train 14 is provided with a count wheel 25 having two adjoining sets of notches 26 for each hour, the notches being adapted to be engaged by a counting arm 27 having its arbor 28 journaled on the framework 10. On the arbor 28 is secured a locking arm 29 controlling a striking wheel 30 having pins 31 adapted to engage an arm 32 forming an extension of the hammer 20 to actuate the latter. The 90 arbor 28 is also provided with a stop arm 35 adapted to engage a stop pin 36 on a wheel 37 in mesh at all times with a pinion 38 attached to an arbor 39 carrying a governor 40. A second governor 41 of larger size 95 than the governor 40 is mounted on an arbor 42 carrying a pinion 43 adapted to move into and out of mesh with the wheel 37. One end of the arbor 42 is journaled on the 100 front plate of the framework 10 while the other end of the said arbor 42 is journaled in an arm 45 (see Figs. 1 and 3) pivoted at 46 on the rear plate of the framework 10. The arm 45 is pressed on by a spring 47 and its swinging movement is guided by a guide-way 48 attached to the framework 10. The arm 45 is provided with an extension arm 50 engaged by one end of a lever 51 fulcrumed at 52 on the framework and pivotally connected at its other end by a link 53 with an arm 54 fulcrumed at 55 on the framework 10, as plainly shown in Figs. 2 and 4. The 105 110

arm 54 is adapted to be engaged by an arm 56 secured to or forming part of the hour arbor 16 to impart a swinging motion to the arm 54 at the half hour whereby the link 53 imparts a swinging motion to the lever 51 which imparts a swinging motion to the arm 45 (see Fig. 3) and thus lifts the pinion 43 out of mesh with the wheel 37. It is understood that when this takes place the hammer 20 is actuated at an accelerated speed as the wheel 37 is then only governed in its speed by the governor 40 while the other governor 41 is inactive for the time being. It is further understood that on the hammer 20 striking the full hour both governors 40 and 41 are in action and consequently the hammer 20 sounds the gong 22 slowly in contradistinction to the fast striking movement at the half hour. Owing to the double set of notches 26 in the count wheel 25 the beats of the hammer 20 for the full hour are the same as the beats for the half hour, only in the latter case the beats are in rapid succession while for the full hour the beats are comparatively slow.

The hammer 21 has its arbor 60 provided with an arm 61 extending on the side of the arbor 16 opposite the one on which the arm 54 is located. The arm 61 is adapted to be engaged by the arm 56 and is provided on its free end with a transversely extending pin 62 engaged by an arm 63 depending from an arbor 64. The arm 63 is provided at its free end with an angular lug 65 (see Fig. 5) adapted to be engaged by a double armed cam 66 attached to the hour arbor 16. The arm 63 forms part of the stop arm 67 adapted to engage the pin 36. The arbor 64 carries a lifting arm 68 engaging the counting arm 27 to lift the latter out of engagement with the count wheel 25 at every full hour and each half hour owing to the two-armed cam 66 employed for the purpose. It is understood that the cam 66 is provided with more arms if the quarter, half and three-quarter hour is to be sounded, and the count wheel 25 is then provided with additional notches for the purpose. The arbors 24, 60, 28 and 64 are pressed on by suitable springs 70, 71, 72 and 73, respectively. By the arrangement described, the half hour is sounded by the arm 21 on the bell 23, prior to the full hour being repeated, by the hammer 20 striking the gong 22.

55 The operation is as follows:

When the clock is running then the full hours are sounded in slow beats by the hammer 20 on the gong 22. When the half hour is reached then the hammer 21 strikes the half hour on the bell 23 and this action is immediately followed by the hammer 20 repeating the beats of the preceding hour in rapid succession. Thus a person on hearing the striking of the hours and half hours 65 readily knows the correct time without see-

ing the position of the hands on the dial of the clock.

It is understood that the clock striking mechanism is shown and described in conjunction with one type of clock, but it is evident that I do not limit myself to this particular application as the clock striking mechanism may be readily applied to any one of the various types of clocks.

From the foregoing it will be seen that hour repeating means are provided for sounding the full hour and repeating the full hour on a fraction of the full hour, and automatic governing means are connected with the said repeating means whereby the repeated full hour at the fraction of the hour is sounded at an accelerated speed relative to the sounding of the full hour.

Having thus described my invention, I claim as new and desire to secure by Letters Patent:—

1. In a clock striking mechanism, hour repeating means sounding the full hour and repeating the full hour on a fraction of the full hour, and automatic governing means for the said repeating means whereby the repeated full hour at the fraction of the hour is sounded at an accelerated speed relative to the sounding of the full hour.

2. In a clock striking mechanism, hour repeating means sounding the full hour and repeating the full hour on a fraction of the full hour, automatic governing means for the said repeating means whereby the repeated full hour at the fraction of the hour is sounded at an accelerated speed relative to the sounding of the full hour, and means sounding the fraction of the hour at the same speed as the repeated full hour and at a different pitch and immediately before the repeated full hour has been sounded at the fraction of the hour.

3. In a clock striking mechanism, two governors, hour repeating means, and controlling means for the said governors rendering one of the said governors inactive whereby the hour is audibly repeated on a fraction of the hour at an accelerated rate of speed relative to the sounding of the hour.

4. In a clock striking mechanism, two governors of different power, hour repeating means for sounding the full hour and repeating the hour on a fraction of the full hour, and controlling means rendering the high power governor inactive while sounding the repeated full hour and the fraction of the hour to sound the same at an accelerated speed relative to the sounding of the first full hour.

5. In a clock striking mechanism, a striking train having a count-wheel provided with hour repeating means, and two governors, of which one is in gear at all times with the said striking train and the other

is periodically out of gear with the said striking train, and means moving the said other governor periodically out of gear.

6. In a clock striking mechanism, a striking train having a count-wheel provided with hour repeating means, two governors of different power, of which the low power governor is at all times in gear with the said striking train and the high power governor is thrown out of gear with the said striking train during the time a fraction of an hour is sounded and the full hour is repeated at a fraction of the hour, and two sounding devices of different pitch, the full hour and the repeated full hour being sounded by one sounding device and the fraction of the hour being sounded by the other sounding device.

7. In a clock striking mechanism, a striking train having a count-wheel provided with hour repeating means, two governors of different power of which the low power governor is at all times in gear with the said striking train, a spring-pressed swing arm

engaging the high power governor, a lever 25 engaging the said swing arm to move the high power governor periodically out of mesh with the said striking train, a link pivotally connected with the said lever, a pivoted arm connected with the said link, 30 and a cam on the hour arbor and adapted to engage the said pivoted arm at a fraction of the full hour.

8. In a clock striking mechanism, a striking train having a counting wheel provided 35 with hour repeating means, a pinion in mesh with one of the gears of the train and carrying a governor, a second pinion carrying a governor and meshing with the said gear, a pivoted and spring pressed member in 40 which one end of the arbor of the second pinion is mounted, and means for swinging the said member from the hour arbor at the fraction of the full hour to move said second pinion out of mesh with the said gear 45 at the fraction of the full hour.

MORRIS DOWLIN.
